VALVE-GEAR FOR RECIPROCATING STEAM-ENGINES.

1,261,925.

Specification of Letters Patent.

Patented Apr. 9, 1918.

Application filed August 21, 1916. Serial No. 116,023.

To all whom it may concern:

Be it known that I, HENRY C. GRAY, of Louisville, Jefferson county, Kentucky, have invented new and useful Improvements in 5 Valve-Gears for Reciprocating Steam-Engines.

My invention relates to improvements in that type of valve gear known as the Walschaert valve gear, wherein the movement 10 of the valve is effected both from the driving wheel and from the piston-rod. In the Walschaert type of valve gear, the motion of the piston-rod, through intermediate means, modifies the motion derived from the 15 driving shaft, so as to produce what is known as "lead." The meaning of this term will appear later. The "lead" produced by the Walschaert valve gear remains constant, whether steam is being admitted for the 20 full stroke of the piston, or a fractional part thereof. This want of variation is a disadvantage, and one of the objects of the present invention is so to modify the Walschaert valve gear, that the "lead" will vary, 25 the variation being dependent upon the point at which cut-off is effected; that is, so that a different "lead" will be secured when steam is being admitted during the full length of the stroke than is secured 30 when it is being cut off, and so that the amount of "lead" will be variable according to the part of the stroke at which cut-off is effected.

The commonest application of this type of 35 valve gear is to steam locomotives of the ordinary type, having cylinders in which pistons reciprocate, piston rods attached to the pistons, and driving wheels revolving on shafts or axles, valves by which steam is 40 admitted to the cylinders, and by which it is cut-off, valve stems, and other features in common use on locomotives.

I attain the objects of my invention by the mechanism illustrated in the accompanying drawings in which—

Figure 1 is a side view of the mechanism showing the cylinder and the valve chest in cross-section.

Fig. 2 is an end view of the hanger at 50 X X, showing the guides and valve stem in cross-section.

Fig. 3 is a side view of the apparatus, which, like Fig. 1, shows the cylinder and steam chest in section. Unlike Fig. 1 it shows the steam chest and cylinder broken 55 off at the front end, and shows the link, later described, with the link bracket piece removed. Fig. 3 also differs from Fig. 1 in that it represents the piston at half stroke, instead of showing the crank on 60 dead center, and also shows the link block.

Both in Fig. 1 and Fig. 3, for simplicity and compactness, certain parts are shown as broken.

Fig. 4 is an enlarged view of the detail 65 adjacent to the point where the combination lever and the radius rod (later referred to) are connected, with the guide pieces partially cut away so as to show certain parts they would hide.

Fig. 5 is a side view of the guide blocks later referred to, and Fig. 6 an end view thereof.

Fig. 7 is a top view of the valve-stem-cross-head-driving-block, Fig. 8 an end view of 75 the top portion of the same, Fig. 9 a side view of the top portion of same, Fig. 10 a side view of the bottom portion of same, and Fig. 11 a plan of the bottom portion of same.

Fig. 12 is an end view of one of the slides, Fig. 13 a top view thereof, and Fig. 14 a side view thereof.

Fig. 15 is an end view of the valve-stem-cross-head, Fig. 16 a side view thereof and 85 Fig. 17 a top view.

Similar figures refer to similar parts throughout all of the views.

A¹ is the cylinder, A² the piston adapted to reciprocate therein, A³ the piston rod, 90 A⁴, the cross-head, A⁵ the connecting rod, A⁶, the cross-head guide, A⁷ the crank, A⁸ the eccentric crank, A⁹ the crank pin, A¹⁰ the driving shaft, in this case the axle of the driving wheel of the locomotive.

B¹ is the eccentric rod, pivoted at B² to the eccentric crank A⁸ and at B³, to the foot, B⁴, of the link B⁵, which is pivoted at the trunnion B⁶; B⁷ is the link bracket piece, which does not appear in Fig. 3, this part 100 of the link structure having been removed so as to show the block B⁸, which is adapt-

ed to move back and forth inside the slot in the link B^3 . B^9 is the radius rod, connected with the block B^8 so as to be actuated thereby at the pivot B^{10} . B^{11} is the 5 lifting arm, and is pivotally connected at one end at B^{12} , with a sleeve in which the radius rod B^9 is adapted to slide and at the other end is fixed to the reversing arm B^{13} , which turns on the reversing shaft B^{14} , and is pivoted at B^{15} to the reach rod B^{16} .

The radius rod B^9 terminates, in the form shown, in a transverse cylindrical extremity, B^{17} , designed to fit in between the forks B^{18} (see Fig. 4) which constitute the upper 15 portion of the combination lever B^{19} . The pin C^{22} passes through appropriate borings in the said extremity B^{17} of the radius rod B^9 , the combination lever and the blocks C^{21} , forming the pivot by means of which the 20 radius rod and combination lever are connected. Said combination lever B^{19} is pivoted at B^{20} to the cross-head link B^{21} which in turn is pivoted at B^{22} to the cross-head arm A^{11} , fastened rigidly to the cross 25 head A^4 .

The steam chest C^1 has a steam chamber C^2 in its interior, with a steam inlet-opening C^3 and a valve cylinder C^4 in which the valve piston C^5 is adapted to reciprocate. 30 Steam inlet ports C^6 , and steam exhaust ports C^7 , are provided in the wall of the steam chest C^1 . To the valve piston C^5 is attached the valve stem C^8 , which is rigidly connected to the valve-stem-cross-head C^9 35 (see Fig. 4). This valve-stem-cross-head, as shown in Fig. 4 and also in Figs. 15, 16 and 17, has two deep wings or flanges having an inner clearance so that the valve-stem-cross-head-driving-block C^{10} fits in between. The said valve-stem-cross-head C^9 also has slits in the sides thereof as shown at C^{10} , and a projection C^{11} which is bored for the reception of a pin, C^{12} , which passes through said projection C^{11} of said cross-head C^9 , and also through the guide blocks C^{13} . The slides C^{14} , appearing in Fig. 4 and Figs. 12, 13 and 14, are adapted to slide on forks, B^{18} , forming the upper end of the combination lever B^{19} . Said slides are provided with cylindrical projections C^{15} , and are bored so as to accommodate the pin C^{12} , which, with the projections C^{15} , connects the two slides C^{14} . The cross-head C^9 , and the slot C^{10} , therein, are of such dimensions 55 that the connections between the two slides, C^{14} , easily slide in said slots.

The valve-stem-cross-head-driving-block C^{10} , as shown in Figs. 1, 3, 4, 7, 8, 9, 10 and 11, is composed of an upper portion C^{17} and 60 lower portion C^{18} , and incloses a rectangular opening such that the suspended controlling bar, later referred to, can slide therein. The upper portion C^{17} has a lug or projection C^{19} thereon, of such dimensions that it slides 65 in the slot C^{10} in the valve-stem-cross-head

C^9 . The valve-stem-cross-head-driving-block C^{10} also has a projection C^{22} at the top, which is suitably bored so that the pin C^{20} may pass through said boring.

The guide pieces B^{23} are provided with 70 grooves adapted for the blocks C^{13} and C^{21} to slide therein, the purpose of these guide pieces being to support the weight of the various parts nearby. To the guide pieces B^{23} , are attached the hangers B^{24} , at pivots B^{25} , and at B^{26} ; the said hangers, B^{24} , are pivoted to the suspended controlling bar B^{27} . Said suspended controlling bar B^{27} is connected by the shifting rod B^{28} , with a point on the reversing arm B^{13} . 80

The operation of the device is as follows:

The piston being in position shown in Fig. 1, and the steam chamber C^2 being full of steam it will be seen that by reason of the "lead" shown at C^{22} , some steam will be 85 entering the cylinder behind the piston before the stroke begins. This amount by which the steam port is opened when the piston is at the end of its stroke is called "lead". It will be seen that any motion 90 of the piston, through the piston-rod, cross-head, the connecting rod, crank, shaft and eccentric crank will produce a movement in the foot B^4 of the link. It will also be seen that the position of the block in the 95 link is capable of being shifted by moving the reversing arm with the reach rod, and that the position of the block in the link will determine the extent to which the rocking motion imparted to the link by the eccentric rod will cause motion in the radius rod; when the point of attachment between the block and the radius rod is in line with the axis of the attachment on which the link rocks, or is pivoted, then the rocking of the 100 link will impart no motion to the radius rod. However, if the block is shifted off this point, the rocking motion of the link will impart motion to the radius rod, the extent of said motion varying with the position of 110 the block. The reciprocating motion imparted to the radius rod will be communicated to its other extremity.

Any motion of the piston rod, as will be seen by reference to the drawings, results 115 not only in motion tending to drive the shaft A^{10} , but by reason of cross-head arm A^{11} and the cross-head link B^{21} , produces motion in the combination lever B^{19} , which is, as before stated, pivoted to the radius 120 rod B^9 . It will, therefore, be seen, that any point on the combination lever except the point where it is pivoted to the radius rod, will have motion similar to the motion which is being imparted through the radius 125 rod, except that such motion is modified by the varying position of the combination lever B^{19} .

Since the valve stem is driven from the combination lever, it receives from some 130

point in the combination lever a displacement which is equal to the displacement of that point in the combination lever, measured with reference to the axis of the valve stem; that is, the movement of the valve stem will be equal to that component of the motion of said point in the combination lever, which is parallel to the axis of the valve stem. If the valve stem had been attached 5 to the end of the radius rod, and the block occupied the position which it occupies in Fig. 1, it is evident that the "lead" shown at C⁹ would be different or would not exist at all, the said "lead" being due, as an examination of the drawing will show, to the inclination of the combination lever; that is, in the Walschaert type of valve gear, dependence for the necessary "lead" is placed on the combination lever to which the valve stem is 10 attached. In the ordinary type of Walschaert valve gear, the motion of the valve piston and valve stem is governed by some one point of the combination lever to which it is attached, and the resulting "lead," after 15 the apparatus is once adjusted, does not vary at all. No matter what the position of the block B⁸ is; no matter whether steam is admitted during the full length of the stroke or cut off at some intermediate point, the 20 "lead" will be the same. The amount of the "lead" will, of course, vary with the ratio which exists between two distances, to wit, the distance from the center of the pivot B²⁰, where the combination lever is connected 25 with the link B²¹ and the center of the pivotal connection between the combination lever B¹⁹ and radius rod B⁹ on the one hand, and on the other hand the distance measured 30 along the combination lever from the center of said pivot C²³ between radius rod and combination lever and the point in the combination lever which controls the motion of the valve stem C⁸. In the ordinary Walschaert type of valve gear, these two distances 35 are fixed and invariable after the machine is put together. In the applicant's device, this ratio is made variable, as will be seen, through the slide structure, which is 40 adapted to slide along the combination lever 45 and move with same so that a change occurring in the position of this slide structure brings it about that the motion of the valve stem corresponds to a new point in the combination lever, and produces a change in the 50 ratio of the two distances before described. 55

In applicant's device, further, the shifting (along the combination lever) of the slide structure from which the valve stem is actuated, is produced by the rising or falling of 60 the suspended controlling bar B²⁷, the rising or falling of which is brought about through the operation of the reversing lever B¹⁸, which is also the agency by which the cut-off of steam is regulated. Therefore applicant's device furnishes a means by which one

motion of the reach rod will at the same time produce a change as to the admission of steam into the cylinder, and a change in the amount of "lead" which is provided for.

With reference to the manner in which the raising or lowering of the suspended controlling bar B²⁷ actuates the sliding structure which controls the motion of the valve stem and the point in the combination lever whose motion controls the motion of the valve stem, 70 reference to Fig. 4 will show that a raising of the suspended controlling bar B²⁷, which slides in the valve stem-cross-head-driving-block C¹⁶, raises the pin C²⁰ and slides C¹⁴, which will move in the slot C¹⁰ in the side 75 wings of the cross-head C⁹ so that the motion of the combination lever, being communicated to the slide C¹⁴, will operate against the sides of the slot C¹⁰ at a higher 80 point than before and therefore at a point 85 which is closer to the pivot point between the radius rod and combination lever.

In the form of apparatus shown, the adjustment is such that when the block B⁸ is at either extremity of the slot the motion of 90 the radius rod has a maximum travel, and steam will be admitted to the cylinder through the entire stroke; when the block is in either of these positions, the suspended controlling bar is at its highest. This being 95 true, the point in the combination lever whose motion determines the motion of the valve stem is closer to the pivot pin C²³ than it will ever get otherwise. Therefore, when the block is in either of these extreme 100 positions the "lead" will be least. As the block is moved toward the pivot of the link, the limits of travel of the valve piston C⁵ diminish, and the steam is cut off before the stroke 105 is finished. It is evident that as the block 110 is moved toward the pivot of the link, the controlling bar B²⁷ will descend, until the lead will be maximum at mid position.

The principal utility of "lead" in steam engines consists first in the fact that it provides a cushioning effect against battering by reciprocating parts at extreme positions, the steam admitted in advance serving to soften the thrust of the piston; and secondly, in securing a large steam opening during 115 the period when the piston requires more steam; that is, at the early portion of its stroke, thus giving steam in the cylinder at a higher pressure than would be the case if there had been no "lead." The need for the 120 cushioning effect is greatest when the engine is running at high speed, and as the block, when the engine is running at high speed, would not be placed or kept at the extreme position at the bottom or top of the link, but 125 at a point nearer the trunnion than the end of the slot, the applicant's device provides the greater "lead" in that position of the block in which greater "lead" is desirable. Experience has proved that to maintain a 130

constant "lead" of the same extent as is necessary and useful at high speed, is not satisfactory or economical; therefore applicant's device by which the "lead" can be varied according to the part of the stroke at which the steam is cut off is valuable and adds to the effectiveness and economy of the engines to which it is applied.

I am aware that structures have been devised wherein the ratio between the two parts of the combination lever referred to above has been variable, but I am not aware of any device similar to mine. It is to be especially noted that in my device as illustrated the combination lever and radius rod are pivoted so that the pivoting occurs always at the same point of the combination lever and the same point at the radius rod, and that the means for varying the ratio referred to above consists of a connecting structure interposed between the valve stem structure (that is, the valve stem and the cross-head attached thereto, and the combination lever) and that the means which are employed to vary the position of this connecting structure or slide structure with reference to the combination lever, are independent of the combination lever, operating by direct contact with the said connecting structure.

In applicant's device, the relative position of the said connecting means and the combination lever does not depend upon the combination lever, but upon separate means, independent of the position of the combination lever. It provides an adjustable connection between the movable part of the valve and the combination lever, involving the slide structure mentioned above, this slide structure being raised and lowered according to the position of the suspended controlling bar, which engages it. Applicant's device is more useful, more durable, and more easily operated and repaired than any device wherein the adjustment depends upon a raising or lowering of the combination lever, because such attachment to the combination lever for the purpose of raising or lowering, interferes with the free movement of the combination lever, and renders the device more complicated. Applicant's device is also superior to any device wherein the connection between the combination lever and radius rod requires the use of a slot, instead of a simple pivot. It is evident that the use of said slot at the pivot makes it impossible for the ends of the radius rod to be at all times equally distant from the ends of the reversing link, and this inequality will result in having a different lead when the piston is at the front end of the cylinder from that which occurs when the piston is at the other end of the cylinder. An examination will disclose that in applicant's device the parts which are neces-

sarily made heavy are simple in construction and free from complication, the necessary complication occurring, in applicant's device, with reference to the smaller and lighter parts.

In the forms hitherto known in which the combination lever is lifted in effecting the change of ratio above referred to, a change was necessarily involved in the relative position of the combination lever and the two members to which it is pivoted, and both of said members are necessarily caused to move when a change of adjustment is made. All of these parts sustain heavy stresses and are necessarily very heavy, requiring great force to lift or move them. It is found that in applicant's device, the power required for shifting is only a very small fraction of the power required in the other case, because, as explained, the parts to be moved are small and light, and it is also found that the operation of applicant's shifting device does not change the position of the combination lever as regards the cross-head link B^1 or radius rod B^2 . The use of the older form has never been general because of the existence therein of the defects which applicant's device avoids.

I claim as new and desire to protect by Letters Patent the following:

1. In a valve gear for reciprocating steam engines having a piston, principal shaft, and a valve having stationary and movable parts, the combination of a radius rod, a combination lever pivotally connected therewith, means for driving said radius rod and regulating the limits of travel of said radius rod, means for communicating motion and force from the piston to the combination lever, a valve-stem-cross-head connected with the movable parts of the valve, a slide structure slidable on the combination lever, and adapted to actuate said valve stem cross-head, in combination with means adapted to engage said slide structure and thereby change the position of said slide structure.

2. In a valve gear for reciprocating steam engines having a piston, principal shaft, and a valve having stationary and movable parts, the combination of a radius rod, a combination lever pivotally connected therewith, means for driving said radius rod and regulating the limits of travel of said radius rod, means for communicating motion and force from the piston to the combination lever, a slide structure adapted to move with the combination lever and slide thereon, a valve stem fixed to the movable part of the valve, a valve stem cross head fixed to the valve stem, said cross head having a slot of such position and dimensions that as the slide structure slides along the combination lever, a portion of the slide structure will slide in said slot, and so that any movement of the slide structure which has a component in the

direction of the axis of the valve stem, will cause a motion of said cross-head equal to said component.

3. In a valve gear for reciprocating steam engines having a piston, principal shaft, and a valve having stationary and movable parts, the combination of a radius rod, a combination lever pivotally connected therewith, means for driving said radius rod and regulating the limits of travel of said radius rod, means for communicating motion and force from the piston to the combination lever, said combination lever being forked near the point at which it is pivoted to the radius rod, slides, a rod connecting the same, a valve stem fixed to the movable part of the valve, a valve stem cross head fixed to said valve stem and having slots in which the connections of said slides are adapted to move.

4. In a valve gear for reciprocating steam engines having a piston, principal shaft, and a valve having stationary and movable parts, the combination of a radius rod, a combination lever, pivotally connected therewith, means for driving said radius rod and regulating the limits of travel of said radius rod, means for communicating motion and force from the piston to the combination lever, a valve-stem-cross-head, movable parts, slidable on the combination lever and adapted to actuate the valve stem cross-head, a controlling bar so formed and placed as to engage said slidable movable part, and determine the position thereof, said shift rod being connected with the means of driving and regulating the radius rod.

5. In a valve gear for reciprocating steam engines having a piston, principal shaft, and a valve having stationary and movable parts, the combination of a radius rod, a combination lever pivotally connected therewith, means for driving said radius rod and regulating the limits of travel of said radius rod, means for communicating motion and force from the piston to the combination lever, a slide structure adapted to move with the combination lever and slide thereon, a valve stem fixed to the movable part of the valve, a valve stem cross head fixed to the valve stem, said cross head having a slot of such position and dimensions that as the slide structure slides along the combination lever, a portion of the slide structure will slide in said slot, and so that any movement of the slide structure which has a component in the direction of the axis of the valve stem, will cause a motion of said cross head equal to said component and means for so actuating said slide structure that any change in the limits of travel in the radius rod will produce a change in the position of said slide structure with reference to the combination lever.

6. In a valve gear for reciprocating steam

engines having a piston, principal shaft, and a valve having stationary and movable parts, the combination of a radius rod, a combination lever pivotally connected therewith, means for driving said radius rod and regulating the limits of travel of said radius rod, means for communicating motion and force from the piston to the combination lever, said combination lever being forked near the point at which it is pivoted to the radius rod, slides, a rod connecting the same, a valve stem fixed to the movable part of the valve, a valve stem cross head fixed to said valve stem, and having slots in which the connections of said slides are adapted to move and means for so actuating said slide structure that any change in the limits of travel in the radius rod will produce a change in the position of said slide structure with reference to the combination lever.

7. In valve gear for reciprocating engines having pistons, principal shafts, valves and valve stems, an eccentric crank, a pivoted link, means for rocking said link as the eccentric crank revolves, a block slidable in said link, a radius rod pivotally connected with said block, a lifting arm, means for connecting said rod and lifting arm, a reversing arm, a controlling bar shifting rod, said reversing arm being fixed to said lifting arm, and pivotally connected at one point with the reach rod, and at another with the controlling bar shifting rod, a suspended controlling bar pivotally connected with the shifting rod aforesaid, hangers supporting said suspended controlling bar, a combination lever, pivotally connected to the radius rod, means for actuating said combination lever from the motion of the piston rod, a structure slidable along the combination lever, means for connecting said structure with the valve stem so that any motion of same along the axis of the valve stem will be communicated to said valve stem, and means for causing said slidable structure to move along the combination lever according as the suspended controlling bar rises or falls.

8. In a valve gear for reciprocating steam engines, having pistons and principal shafts, a radius rod, means for actuating same from the principal shaft, a pivoted link, a block movable therein, means for shifting the position of said block, means for connecting said block with the radius rod, means for moving the suspended controlling bar so as to vary its distance, within limits, from the radius rod, said means being connected and actuated so that the position of the controlling bar changes when the position of the block changes, a combination lever pivoted to the radius-rod, means for actuating said combination lever from the piston, means for actuating the valve stem so that its motion equals the displacement of some point in the combination lever so far as said dis-

placement is in the direction of the axis of the valve stem, and means for so connecting the suspended controlling bar and the valve-stem-actuating-means that when the suspended controlling bar moves so as to vary its distance from the radius-rod, such movement will cause a movement of the

valve-stem actuating means along the combination lever.
